UNITED STATES PATENT OFFICE.

LOUIS J. RUSSELL, OF RICHMOND HILL, NEW YORK.

PAPER BOX.

Application filed July 8, 1927. Serial No. 204,164.

The invention relates to a paper box, and more particularly to the class of foldable combination package nesting and display boxes, cartons or the like.

5 In the transit of packaged articles, for example toilet preparations, it has been customary to have the individual articles contained within separate wrappers or packages and these are placed within a box for shipment, and upon delivery considerable labor is required for the removal of the individual packages from such box. Furthermore, in the individual packaged article it is impossible to group the same whereby a group of 15 such articles may be held intact either for the exhibit of the packaged articles or for expediting the handling thereof when packing and unpacking the same. When the articles are individually packaged and placed 20 within or upon a show case or other holder for exhibiting the same, there is required a separate placard or display card to be associated with the packages which ordinarily becomes separated or misplaced with respect to the 25 packaged articles on display.

It is the aim of the present invention to construct a box, carton or the like wherein individually packaged articles can be nested in a group so that the said grouped packaged articles can be placed on display as a unit and when a sale of an article is had the packaged one can be removed from the group without disturbing the remaining ones in the nest. The nesting box, carton or the like, 30 carries a placard or flap designed to bear advertising matter relating to the packaged group of articles therein, which placard or flap is separable correspondingly to the points of separation of the box, carton or the like, so that a portion of the placard or flap on separation of an individual package article from the group remains a part of the separated section 35 of the unit carrying the individual package article.

40 The invention mainly comprises a box, carton or the like, for the nesting or grouping of packaged articles therein and which may be separated along scored or weakened lines into sections carrying individual packaged articles of the group, the box, carton or the like being formed from paper and foldable with a placard or display tab constituting a unitary part thereof, the said placard or tab being separable correspondingly to the sections, 45 and the separable portions of the placard or

tab carrying suitable advertising matter related to the articles. Thus in the use of the box, carton or the like the packaged articles can be conveniently grouped to form a single package for transportation and sale, as the 60 individual packaged articles can be readily separated from the others of the group without the removal of the articles from the box, carton or the like when placed on display.

Other objects of the invention will be in 65 part obvious and in part hereinafter pointed out.

The invention consists in the features of construction, combination and arrangement of parts as will be hereinafter more fully described, illustrated in the accompanying drawing showing the preferred embodiment of the invention, and pointed out in the claims hereunto appended.

In the accompanying drawing:

70 Figure 1 is a perspective view of the box, carton or the like constructed in accordance with the invention, shown in position on display.

75 Figure 2 is a vertical transverse sectional view through the box, carton or the like showing by full lines the placard or tab in lowered position and by dotted lines in upright or raised position.

80 Figure 3 is a fragmentary vertical longitudinal sectional view showing the packaged individual articles within the body of the box, carton or the like.

85 Figure 4 is an end elevation showing the box, carton or the like folded flat.

90 Similar reference characters indicate corresponding parts throughout the several views in the drawing.

95 Referring to the drawing in detail, the invention comprises generally a tubular formed body A and a placard or tab B, these being hereinafter more fully described.

100 The body A and placard or tab B are preferably made from a single piece of material, either stiff paper, cardboard or the like, although the same may be made from any other suitable or desirable material. The piece of material in blank form is preferably of substantially rectangular shape and in the main is folded to provide the body A, with bottom 105 5, top 6, front 7 and back 8, respectively, these following the folds 9 effected by suitable weakened or creased lines common to foldable box structures of the paper kind.

110 The placard or tab B is formed by an ex-

- tension 10 of the top 6 of the body A, and is hinged or swingingly associated with the body A through the medium of a crease or fold 11. The back 8 of the body A is joined 5 to the extension 10 providing the placard or tab B by an overlap 12, which is pasted or otherwise secured to the rear face of the extension 10 following the fold or crease 11 between the latter and the top 6 of the body A.
- 10 The body A is capable of nesting a group of individual packaged articles of any preferable number, each article containing package being exemplified at 13, the body 10 being open at opposite ends so that the article contained packages 13 can be introduced therein from either open end, as will be clearly apparent.

15 Formed transversely in the body A through the bottom 5, top 6, front 7, and back 8, including the overlap 12, are score or weakened lines 14, these being spaced apart correspondingly to the points of separation of the packages 13 containing the articles when placed within the body A so that when it is desired 20 to separate an individual packaged article from the group, the body A can be broken along the weakened or score lines 14 between the package to be separated and the adjacent package of the group within the body A, thus 25 eliminating the necessity of pushing the group of packages from within the body so that an individual packaged article may be procured or had.

30 The placard or tab B formed by the extension 10 has score or weakened lines 15 forming continuations of the score or weakened lines 14 in the body A so that when a section of the body A is separated a corresponding section of the placard or tab B will be simultaneously separated therewith, the section of the body A and the portion corresponding thereto of the placard or tab B being broken on the score or weakened lines 14 and 15 respectively therein.

35 The placard or tab B throughout the front face thereof, between the score or weakened lines 15, preferably may contain advertising matter relating to the packaged articles grouped within the body A in the display of 40 the grouped packaged articles, and likewise the separable sections 16 of the body A between the score or weakened lines 14 therein on selected or all outer faces thereof may contain advertising matter for the packaged articles within the body A. Where advertising matter is employed upon the tab B, it is 45 desirable that the advertising matter between adjacent weakened portions 15 shall be complete individually so that each separable section shall contain a complete advertisement and the severance of one section does not operate to spoil the advertising effect or the utility of the balance of the article. Of course it is optional with the user of the box, 50 carton or the like hereinbefore described, to

have the body A and the placard or tab B contain advertising matter and the nature thereof.

55 The box, carton or the like, including the body A and the placard or tab B, is normally folded flat in the position shown in Figure 4 of the drawing and said body A can be readily set up by the unfolding to the positions shown in Figures 1 to 3 inclusive, and likewise the tab or placard can be lowered on to the body A as shown in Figure 2 or raised to the position shown in Figures 1 and 3 of the drawing, for display purposes.

60 It is to be understood, of course, that the size of the box, carton or the like can be varied and likewise the shape of the body A and placard or tab B correspondingly to the nature of the packaged articles.

65 From the foregoing it is thought that the construction and manner of use of the invention will be clearly understood, therefore a more extended explanation has been omitted.

What is claimed is:

1. As an article of manufacture, a box comprising a foldable body having opposite 70 opened ends, provided with weakened portions between said ends for separation of the body into sections, and a display placard forming a continuation of the body and having weakened portions coincident with the weakened portions of the body, said display placard having advertising matter arranged thereon in such a way that severance of one of said sections does not interrupt the continuity of the remainder.

75 2. As an article of manufacture, a box comprising a foldable body having opposite opened ends, provided with weakened portions between said ends for separation of the body into sections, and a display placard forming a continuation of the body and having weakened portions coincident with the weakened portions of the body, said body and placard being formed from a single piece of material, said display placard having advertising matter arranged thereon in such a way that severance of one of said sections does not 80 interrupt the continuity of the remainder.

85 3. A box of the kind described comprising a foldable body formed from a single piece of material longitudinally creased to provide bottom, top, front and back, and an extension on the top forming a placard and foldable on to said top, the back of the body being joined with the extension, being separable into sections and said body and extension having score lines coincident with each other transversely thereof at spaced intervals apart, said display placard having advertising matter arranged thereon in such a way that severance of one of said sections does not interrupt the continuity of the remainder.

90 4. An article of the class described comprising a box portion adapted for reception of articles for sale, said box portion having

weakened portions between adjacent articles and dividing the box portion into sections, and a placard extending from said box portion and having weakened portions coincident with the weakened portions of the box portion, said weakened portions dividing the placard into sections corresponding to the

sections of the box portion, each of said placard sections containing advertising matter complete in itself.

In testimony whereof, I have signed my name to this specification this 5th day of July, 1927.

LOUIS J. RUSSELL.
